AUTOMATIC TRAIN CONTROL DEVICE

Clyde C. Farmer, Pittsburgh, and Ellis E. Hewitt, Edgewood, Pa., assignors to The Westinghouse Air Brake Company, Wilmerding, Pa., a corporation of Pennsylvania

Application June 26, 1935, Serial No. 28,390

38 Claims. (Cl. 303—18)

This invention relates to brake controlling apparatus for railway trains and more particularly to that type of control apparatus for controlling the brakes of the train either manually by the use of the usual brake valve device or automatically through the medium of automatic train control apparatus which is adapted to function in accordance with traffic conditions, which train control apparatus may comprise fluid pressure apparatus adapted to be electrically controlled from the trackway.

One object of the invention is to provide an improved brake controlling apparatus of the above mentioned type.

In ordinary train service various train operating conditions are encountered, such for instance as variations in the length and weight of trains and variations in rail and grade conditions, which make it necessary to exercise a great deal of skill in applying the train brakes to bring the train to a stop or to a predetermined slow speed without causing harsh and dangerous slack gathering or closing shocks.

Since the engineman will naturally be aware of these conditions it is very desirable, in order to obtain the best results, that the brake application be under his direct control instead of being under the control of the automatic train control apparatus which, after all, being a mechanical device, cannot duplicate manual control under all train and track conditions. It will thus be understood that upon a danger signal indicating a change in traffic conditions, the engineman must cause an application of the brakes to be effected within a predetermined period of time and that if he fails to do this, the automatic train control apparatus functions to cause the brakes to be applied.

With this in mind, another object of the invention is to provide in combination with the engineman's automatic brake valve device and the automatic train control apparatus, improved means for suppressing an automatic train control application of the brakes when the automatic brake valve device is moved by the engineman to a brake applying position.

In the usual fluid pressure brake systems, an application of the brakes is effected upon a reduction in brake pipe pressure and is released upon an increase in brake pipe pressure. When automatic train control apparatus is employed the reduction in brake pipe pressure is effected through the medium of either the automatic brake valve device or the train control apparatus. To effect a release of the brakes the automatic brake valve

device is moved to either running position or release position in which fluid under pressure is supplied to the brake pipe. Since the automatic train control apparatus is adapted to function to effect a reduction in brake pipe pressure when a danger signal is encountered, it is imperative that the supply of fluid to the brake pipe be cut off, and another feature resides in the provision of means operating in conjunction with the automatic train control apparatus for moving the automatic brake valve device from either release position or running position to lap position to cut off the supply of fluid under pressure to the brake pipe when the train control apparatus is set in operation to effect an application of the brakes.

Other objects and advantages will appear in the following more detailed description of the invention.

In the accompanying drawings, Fig. 1 is a diagrammatic view, mainly in section, of a portion of a train brake equipment embodying the invention; Fig. 2 is a diagrammatic vertical sectional view of the engineman's automatic brake valve and brake valve pedestal, certain of the devices associated therewith being shown in elevation; Fig. 3 is a fragmentary plan view of the engineman's automatic brake valve device, a portion of the valve casing being broken away to illustrate certain features of the device; Fig. 4 is a view somewhat similar to Fig. 3, a portion of the casing being broken away on the line 4—4 of Fig. 2; Figs. 5 to 9 inclusive are fragmentary vertical sectional views of the automatic brake valve device illustrating the rotary valve thereof in its several brake controlling positions; Fig. 10 is a fragmentary diagrammatic sectional view of a portion of the application valve mechanism of the apparatus and illustrates a modification of the mechanism; Fig. 11 is a diagrammatic view, mainly in section, of a portion of a train brake equipment embodying another form of the invention; Fig. 12 is a detail vertical sectional view of a portion of the automatic brake valve device, taken on the line 12—12 of Fig. 11, and Fig. 13 is a detail horizontal sectional view of a portion of the automatic brake valve device, taken on the line 13—13 of Fig. 12.

As shown in the accompanying drawings, the train brake equipment may comprise a brake pipe 1, an engineman's brake valve pedestal which is secured in place at the engineman's station and which, as shown in Fig. 2, supports an automatic brake valve device 3, an independent brake valve device 4, an equalizing discharge valve device 5,

a feed valve device 6, a reducing valve device 7 and a relay valve device 8. The equipment also comprises a timing mechanism 9, a brake application valve device 10, a suppression valve device 11, an equalizing reservoir 12, a timing reservoir 13 which is associated with the suppression valve device, a timing reservoir 14 which is associated with the application valve device, a first reduction reservoir 15 and a second reduction reservoir 16. The equipment also includes a brake valve actuating mechanism 17 which is adapted to operate automatically, when an automatic train control application of the brakes is initiated, to move the engineman's automatic brake valve device from either release position or running position to lap position, as will hereinafter more fully appear.

Although not shown in the drawings, the train brake equipment may include, in addition to the above mentioned parts, mechanisms and devices, a distributing valve device, the brake apparatus on each car of the train and a main reservoir. The distributing valve device may be of the same type as that disclosed in Patent No. 1,975,264 issued October 2, 1934 to Clyde C. Farmer and the brake apparatus may be of the same type as that disclosed in said patent. Both the distributing valve device and the brake apparatus are controlled according to variations in brake pipe pressure in the usual manner in effecting the application and release of the brakes, that is to say, a reduction in brake pipe pressure causes an application of the brakes on the locomotive and cars to be effected and an increase in brake pipe pressure causes a release of the locomotive and car brakes.

The brake valve and brake valve pedestal arrangement is what is known as the "No. 8 E. T." brake valve arrangement and is quite similar to the brake valve arrangement disclosed in the above mentioned patent.

The automatic brake valve device 3 may comprise a casing having a valve seat section 20 and a cap or cover section 21 which sections are secured together and to the pedestal 2. The cover section 21 is provided with a bore containing a rotary valve 22, the face of which slidably contacts with the valve seat carried by the seat section 20, and the peripheral edge surface of which slidably contacts with the cover section 21 within said bore. The rotary valve 22 is operatively connected with the inner end of a rotatable operating stem 23 suitably journaled in the cover section 21 of the casing. The outer end of the stem 23 terminates outside of the cover section 21 and has secured thereto an operating handle 24 through the medium of which the stem and thereby the rotary valve is rotated. The handle is provided with the usual spring-pressed plunger 25 which is adapted to cooperate with a notched quadrant 26, carried by the cover section 21, to yieldably resist movement of the handle from one brake controlling position to another and to indicate to the engineman when the handle is in a desired control position.

Beneath the handle 24 and adjacent thereto, there is secured to the operating stem 23, for rotation therewith, a cam 27 having a peripheral cam face preferably comprising curved concentric surfaces 28 and 29, the radius of the surface 28 being less than that of the surface 29. The cam face also comprises a sloping surface 30 which merges into the surfaces 28 and 29.

The cover section 21 of the casing is provided with a valve chamber 31 containing an exhaust

valve 32 having a fluted stem 33 which is slidably guided in a bushing 34 mounted in the casing, said valve being operative to control communication from the valve chamber 31 to a recess 35, which recess, as shown in Fig. 4 of the drawings, is connected, through the restricting passage of a choke plug 36, to the atmosphere. The recess is also connected to a control pipe and passage 37 for reasons which will hereinafter be fully described. One end of the bushing 34 is provided with an annular seat rib 38 on which the valve 32 is adapted to seat to close communication from the valve chamber 31 to the recess 35, said valve being constantly urged toward the seat rib by the action of a coil spring 39 contained in the valve chamber 31.

For the purpose of controlling the operation of the exhaust valve 32, a member 40 is provided which, in the present embodiment of the invention, is contained in the recess 35 and which, at one end, is pivotally mounted on a pin or projection 41 carried by the cover section 21 of the casing. The other end of the member 40 is adapted to operatively engage the end of the fluted stem 33 of the exhaust valve 32. The member 40, intermediate its ends, is provided with a lug 42 which is adapted to be operatively engaged by the surfaces 29 and 30 of the peripheral face of the cam 27 for controlling the operation of the member and thereby the exhaust valve 32.

From an inspection of Fig. 4 of the drawings it will be observed that, with the movable parts of the automatic brake valve device 3 in either running position or release position, there will be a slight clearance between either the end of the lug 42 and the surface 28 of the cam 27 or the end of the valve stem 33 and the free end of the member 40, thus insuring the proper seating of the exhaust valve 32 by the action of the spring 39.

When the handle 24 of the automatic brake valve device is being moved to the 1st service position, the surface 30 of the cam 27 engages the lug 42 and causes the member 40 to rock about the projection 41 in a clockwise direction, such movement of the member unseating the exhaust valve 32 against the opposing pressure of the spring 39. With the brake valve handle 24 in 1st service position or in either lap, service or emergency position, the surface 29 of the cam 27 is in engagement with the lug 42, so that the member 40 is maintained in position to hold the exhaust valve 32 open.

The cover section 21 of the automatic brake valve casing is provided with a recess which is open to the periphery of the rotary valve 22, the walls of the recess and the peripheral surface of the valve defining a chamber 43 which, in the several brake controlling positions of the rotary valve, is in communication with a chamber 44 at the back of the rotary valve by way of one or more cavities 45 in the back of the valve. The rotary valve chamber 44 is constantly open to a fluid pressure supply passage 46 leading from the feed valve device 6.

For the purpose of controlling communication from the main reservoir to the chamber 43 and consequently to the rotary valve chamber 44, a valve piston 47 is provided which is slidably mounted in the cover section 21 of the brake valve casing. This valve piston is provided, at one end, with a valve 48 which is adapted to seat on an annular seat rib 49 carried by the cover section of the casing and close a passage 50 leading to the chamber 43. At the outside of the seat rib 49, the face of the valve piston and the cover sec-

tion 21 define a chamber 51 with which the main reservoir is in constant open communication by way of a pipe 52 and a passage 53. The valve piston, at its other end, is provided with a valve 54 which is adapted to seat on a gasket 55 which is clamped between the casing sections 20 and 21. The chamber 51 is in constant communication through a small or restricting port 56 in the valve piston with a chamber 57 at the other side of the 10 valve piston, which chamber 57 is open to a passage 58 leading to the seat of the rotary valve 22. Contained in the chamber 57 is a coil spring 59 which acts to urge the valve piston in the direction toward the seat rib 49.

15 The equalizing discharge valve device 5 may comprise a casing in which there is operatively mounted a piston 70 having a stem 71 which is slidably guided by the casing within a bore 72. At one side of the piston 70 is a piston chamber 20 96 with which the equalizing reservoir 12 is in constant communication by way of a pipe 73, a passage 74 and a passage 75, said passage 75 leading to the seat for the rotary valve 22 of the automatic brake valve device. At the other side 25 of the piston there is a chamber 76 which is in constant open communication with a passage 77 leading to the seat for the rotary valve 22 and which contains an exhaust valve 78 which is operative to control communication from the valve chamber 76 to a passage 79 leading to the valve chamber 31 containing the exhaust valve 32. The exhaust valve 78 is provided with a stem 80 which is slidably guided in a bushing 81 carried by the casing. The valve stem extends through 30 the bushing and adjacent its end is provided with a collar 82. Interposed between and engaging the outer face of this collar and the casing is a coil spring 83 which normally maintains the exhaust valve 78 seated as shown in Fig. 2 of the 35 drawings.

Contained in the valve chamber 76 is a bell crank lever which is rockably mounted on a pin 84 carried by the casing, said lever comprising arms 85 and 86. The end portion 87 of the arm 40 85 is substantially spherical in form and is operatively engaged by the piston stem 71 within an opening 88 which preferably extends through the stem. The arm 86 is adapted to operatively engage the inner face of the collar 82 to control the operation of the exhaust valve 78. The arm 85, at a point intermediate its spherical end 87 and the pin 84, is adapted to operatively engage the end of the stem of a supply valve 89 contained in a chamber 90 which is in constant communication with a passage 91 leading from the seat of a rotatable plug valve 92 mounted in the casing section 20 of the automatic brake valve device, said valve 89 being normally maintained seated by the action of a coil spring 93. With 45 the plug valve 92 in the position in which it is shown in Fig. 2, the passage 91 is in registration with a passage 94 in the plug valve, and the passage 94 is in registration with a passage 95 leading to the seat for the rotary valve 22 of the 50 55 automatic brake valve device.

The timing valve mechanism 9 constitutes a part of the train control apparatus and is provided for the purpose of controlling the operation of the application valve device 10. This 50 timing mechanism may comprise a fluid pressure controlled valve portion and an electrically controlled valve portion, which latter portion, as will hereinafter appear, functions in accordance with changes in signal indications to control the 75 operation of the fluid pressure controlled valve

portion and to cause a signal to be produced when a danger zone is encountered to warn the engineer that an automatic train control application of the brakes is about to be initiated.

The fluid pressure controlled valve portion of 5 the timing valve mechanism 9 comprises a double beat valve 101 contained in a chamber 102 and having a fluted stem 103 extending through a chamber 104 at one side of a valve piston 105, and through an opening in a wall 106 of the valve 10 piston and into a chamber 107. Contained in chamber 107 and secured to the end of the valve stem 103 is a collar 108 against which a spring 109 acts, said spring being adapted to operate the double beat valve 101 upon upward move- 15 ment of the valve piston.

Interposed between and engaging the wall 106 of the valve piston and the casing of the timing valve mechanism is a spring 110 adapted to urge the valve piston downwardly and cause a seat 20 ring 111 to engage a gasket 112 as will hereinafter appear.

The double beat valve 101 is also provided with a fluted stem 113 which extends upwardly into a chamber 114. 25

Contained in chamber 114 is a member 115, the upper end of which is slidably mounted in a nut 116 having screw-threaded engagement with the casing. A collar 117 is formed at the lower end of said member, and interposed between 30 the collar and nut is a spring 118, which is adapted to maintain the collar in engagement with the valve stem 113 and to exert a downward force on the stem 113 and consequently on the valve 101. 35

The electrically controlled valve portion of the timing valve mechanism 9 comprises a magnet 119, a valve 120 contained in a chamber 121, and a valve 122 contained in a chamber 123. The magnet upon energization, is adapted to 40 seat valve 120 and unseat valve 122 and when said magnet is deenergized, a spring 124, contained in the chamber 123, is adapted to seat valve 122 and unseat valve 120.

The magnet 119 is adapted to operate in accordance with traffic conditions on a railway and may be governed by current from a circuit or circuits provided in the track rails (not shown), in such a manner that when traffic conditions are favorable, the magnet will be energized and 45 when unfavorable or if the train should be stopped, the magnet will be deenergized.

The magnet valves 120 and 122 are adapted to control the supply and venting of fluid under pressure to and from a timing reservoir or chamber 125, which is connected through a passage 126 to the lower face of the valve piston 105. 50

The brake application valve device 10 may comprise a casing having a piston 127, at one side of which is a piston chamber 128 connected 55 through passages and pipe 129 to the chamber 114 of the timing valve mechanism 9. Contained in the piston chamber and interposed between and engaging the outer face of the piston 127 and the inner surface of the casing is a spring 130 which acts at all times to urge the piston toward its normal position, in which position it is shown in Fig. 1. The piston is provided with a stem 131 adapted to actuate a slide valve 132 contained in a chamber 133 which is constantly connected to the feed valve passage 46 in the brake valve pedestal through a passage and pipe 134 and a passage 135 in the 60 65 brake valve pedestal. The valve chamber 133 and piston chamber 128 are constantly con- 70 75

ected to each other through a restricted port 136 provided in the piston 127.

The brake application valve device also comprises a maintaining cut-off valve device, a 2nd reduction cut-in valve device, and a control device for controlling the operation of these valve devices.

The maintaining cut-off valve device comprises a cut-off valve 137 contained in a chamber 138 which is connected through a passage 139 with the slide valve chamber 133, said valve being at all times urged in a direction toward its seat by a spring 140 contained in the valve chamber 138. The cut-off valve device also comprises a valve 141 which is connected to the cut-off valve 137 by means of a fluted stem 142, said stem passing through a chamber 143 which is connected to a passage 144 leading from the seat for the slide valve 132. The valve 141 is contained in a chamber 145 and is adapted to be engaged by the inner end of a plunger 146, said plunger being provided with a collar 147 which is slidably mounted in the casing. Also contained in chamber 145 is a spring 148 which is interposed between and engages one side of the collar 147 and the casing and which acts to urge the plunger 146 in a direction toward the left hand. The other side of the collar is adapted, as will hereinafter appear, to engage an annular seat rib 149 carried by the casing so as to prevent fluid under pressure which may leak from the chamber 145 past the collar 147 from escaping to the atmosphere by way of any clearance space between the casing and a portion of the plunger 146 which extends through an opening in the casing to the exterior of the casing.

The reduction cut-in valve device comprises a double beat valve 150 which is contained in a chamber 151 which is constantly connected through a passage 152 to a 2nd reduction reservoir 16. The double beat valve has, at one side, a fluted stem 154 which terminates within a chamber 155 and which is subject to the action of a spring 156 contained in the chamber. At the other side, the double beat valve has a fluted stem 157 which extends through an opening in the casing to the exterior of the casing.

The control device comprises a movable abutment in the form of a flexible diaphragm 158 and a follower 159 having a stem 160 which extends through an opening in the casing. Arranged exteriorly of the casing and pivotally secured to the stem 160 is a crosshead 161 which is adapted to operatively engage with the ends of the plunger and valve stem 157 which project beyond an exterior surface of the casing. At one side of the flexible diaphragm there is a chamber 162 which is connected through a passage and pipe 163 to the timing reservoir 14. Leading from the passage 163 to the seat for the slide valve 132 is a passage 164 which, as shown in Fig. 1, is normally connected with the valve chamber 133. At the other side of the diaphragm and containing the follower 159 is a chamber 165 which is open to the atmosphere past the stem 160 of the follower. Also contained in this chamber is a spring 166 which is interposed between and is in operative engagement with the follower and casing, said spring tending at all times, to shift the follower 159 and diaphragm 158 in a direction toward the left hand.

The brake application suppression valve device 11 comprises a casing having a flexible diaphragm 170 mounted therein. At one side of the dia-

phragm is a chamber 171 which is connected to a passage 172 which is in constant open communication with the feed valve pipe 134. At the other side of the diaphragm is a chamber 173 which is connected to a passage 174 which is in constant open communication with the brake pipe 1. Contained in the chamber 173 and operatively associated with the diaphragm 170 is a follower 175 which is subject to the action of a spring 176 also contained in chamber 173. The follower is provided with a stem 169 which is adapted to engage a fluted stem 177 projecting from the right hand side of a double beat valve 178 contained in a chamber 179. Projecting from the other side of this double beat valve and extending into a chamber 180 which is constantly connected through a passage 181 to the atmosphere, is a fluted stem 182 which is operatively engaged by one end of a plunger 183 which is slidably mounted in the casing. Interposed between and operatively engaging the plunger 183 and the casing is a spring 184 which, at all times, tends to urge the plunger and thereby the double beat valve 178 in a direction toward the right hand.

The brake valve actuating mechanism may comprise a cylinder casing 190 which is carried by the cover section 21 of the automatic brake valve device. Operatively mounted in the cylinder casing is a piston 191 having a hollow stem 192 which surrounds a spring 193 interposed between and operatively engaging the rear face of the piston and a non-pressure head 194 which has screw-threaded connection with the rear end of the cylinder casing, said spring tending, at all times, to urge the piston outwardly, i. e., in a direction toward the left hand. The piston stem 192 is provided with an arm 195 which extends through an elongated opening 196 in the cylinder casing and, exteriorly of the casing, is adapted to operatively engage an arm 197 which, in the present embodiment of the invention, is integral with the handle 24 of the automatic brake valve device. At the forward face side of the piston 191 is a piston chamber 198 which is connected through a passage and pipe 199 to a passage 200 leading to the seat for the slide valve 132 of the brake application valve device 10.

The cylinder casing 190 carries a small cylinder casing 201 in which there is operatively mounted a piston 202. At one side of this piston is a chamber 203 containing a spring 204 which acts to normally maintain an annular portion of the forward face of the piston in engagement with a gasket 205. The portion of the piston chamber 206 which is surrounded by the annular seated portion of the piston is connected to the double beat valve chamber 179 of the brake application suppression valve device 11 by way of a passage and pipe 207, a passage 208, a restricting passage in a choke plug 209 and a passage 210. The rear face of the piston is provided with an annular groove which contains an annular valve gasket 211 adapted to engage a seat rib 212 carried by the casing. The piston is provided with a fluted stem 213 which extends through an opening in the casing. The outer end of the stem 213 is adapted to engage a spring electric contact member 214 which is carried by the casing, there being suitable insulating material interposed between the member and the casing and also between the piston stem and the member. The contact member 214 is adapted to be moved, by means of piston stem 213, into en-

gagement with a resilient electric contact member 215 also carried by and insulated from the casing. The contact member 215 is adapted to be moved into contact with the contact member 214 by means of the arm 197 when the handle 24 of the automatic brake valve device is moved to service position, the engagement of the arm 197 being with insulating material secured to the contact member.

10 The contact member 214 is connected by a circuit wire 216 to the circuit wire 217 which is connected to one end of the winding of the magnet 119, the opposite end of the winding being connected to ground as shown in Fig. 1. The wire 217 constitutes a portion of a circuit which is controlled according to a trackway indication, as will hereinafter more fully appear.

The contact member 215 is connected by a wire 218 to a spring contact member 219 which is secured to the non-pressure head 194 and which is adapted to contact with a contact member 220 secured to the non-pressure head, suitable insulating material being interposed between the contact members and between the contact member 219 and the non-pressure head 194. The contact member 220 is connected to one terminal of a source of electric current, such, for instance as a battery 221, the other terminal of the source of current being connected to ground. The contact members 219 and 220 are enclosed by an annular flange 222 of the non-pressure head 194 and cover plate 223 secured to the flange.

30 The movement of the contact member 219 into and out of contact with the contact member 220 is controlled by a plunger 224 which is slidably mounted in the non-pressure head 194 and which is controlled by the piston stem 192, the plunger extending through an opening in the non-pressure head and being adapted to be engaged by 40 the end of the piston stem.

In operation the main reservoir (not shown) being charged with fluid under pressure in the usual manner, fluid flows therefrom through pipe 52 and passage 53 to the chamber 51 at one side 45 of the valve piston 47 of the automatic brake valve device, and from said chamber flows through the port 56 in the valve piston to the chamber 57. Since the pressures of fluid acting on both sides of the piston are substantially equal, the pressure 50 of the spring 59 maintains the gasket valve 48 carried by the upper end of the valve piston in seating engagement with the seat rib 49 as shown in Fig. 2. From the passage 53 fluid at main reservoir pressure flows through a 55 branch passage 225 to the feed valve device 6 where the pressure is reduced to that normally carried in the brake pipe 1.

Fluid at the reduced pressure supplied by the feed valve device flows through passage 46 to the 60 rotary valve chamber 44 of the automatic brake valve device. From the passage 46 fluid flows through passage 135, pipe and passage 134 to the slide valve chamber 133 of the brake application valve device 10. From the pipe 134 fluid under 65 pressure flows through passage 172 to the diaphragm chamber 171 of the suppression valve device 11.

Fluid at main reservoir pressure flows from the 70 passage 53 through a branch passage 226 to the reducing valve device 7. The reducing valve device reduces the pressure to a desired degree and fluid at the reduced pressure is supplied through a passage 227, a passage 228, a pipe 229 and a choked passage 230 to the valve chamber 123 of 75 the timing valve mechanism.

Assuming that the train is running on trackway where the traffic conditions are favorable, the automatic brake valve device will be in running position and the magnet 119 will be energized by current flowing through the circuit wire 217 and ground. With the magnet 119 energized, the exhaust valve 120 of the timing valve mechanism is maintained seated and the supply valve 122 is maintained unseated against the opposing pressure of the spring 124. With the valve 122 unseated, fluid at reducing valve pressure supplied to the supply valve chamber 123 flows therefrom to the timing chamber 125 and piston chamber 231 at the lower side of the piston 105 by way of the open valve 122 and its fluted stem, a chamber 15 232, a passage 233, past a ball check valve 234 and and passage 126. Fluid from the passage is also adapted to flow from the passage 233 to the passage 126 by way of a restricted passage 235 which by-passes the ball check valve 234. Fluid under 20 pressure in chamber 231 holds the valve piston 105 in its upper position against the opposing pressure of the spring 110, in which position the upper edge of the valve piston is in sealing engagement with a gasket 236.

The valve piston 105 acting through the medium of the spring 109 and valve stem 103 maintains the double beat valve 101 in its upper or normal position, in which position the chamber 104 at the upper side of the valve piston is connected with the atmosphere past the fluted valve stem 103 through chamber 102 and through an atmospheric passage 237.

With the rotary valve 22 of the automatic brake valve device in running position as shown in Figs. 35 1 and 2, fluid under pressure supplied by the feed valve device to the rotary valve chamber 44, flows from said chamber through a port 238 in the rotary valve 22 and passage 75 to the piston chamber 96 of the equalizing discharge valve device 5. 40 Fluid under pressure also flows from the rotary valve chamber 44 through a port 239 in the rotary valve and passage 71 to the chamber 76 of the equalizing discharge valve device 5. From the port 239 fluid under pressure flows through 45 passage 95, passage 94 in the plug valve 92 and passage 91 to the supply valve chamber 90 of the equalizing valve device 5. The pressures of fluid being equal on opposite sides of the piston 70 the several parts of the equalizing discharge valve 50 device will be in their normal position as shown in Fig. 2, in which position both the exhaust valve 78 and the supply valve 89 are closed.

Fluid under pressure flows from the passage 75 through passage 74 and pipe 73 to the equalizing 55 reservoir 12.

Fluid under pressure flows from the passage 91 through passage 167 and pipe and passage 168 to the seat for the slide valve 132 of the brake application valve device 10.

From the passage 77 fluid under pressure flows through a passage 240 in a plug valve 241 mounted in the section 20 of the casing of the automatic brake valve device and through a passage 242 to a branch of the brake pipe 1 and consequently to 65 the brake pipe. From this branch pipe fluid under pressure flows through passage 174 to the diaphragm chamber 173 of the suppression valve device 11. The pressures of fluid in the chambers 171 and 173 being substantially equal the 70 spring 176 acts to hold the follower 175 and diaphragm 170 in their extreme right hand position as shown in Fig. 1. With the follower in this position the spring 184 acts to hold the double beat valve 178 in its right hand seated position, in 75

which position it closes communication between the chamber 173 and chamber 179 and opens communication from the chamber 179 to the chamber 180 which is connected through passage 181 with the atmosphere.

It will here be noted that since the chamber 179 is open to the atmosphere, as just described, and since the piston chamber 206 of the contact controlling cylinder device is connected to the chamber 179 by way of pipe 207, passage 208, the passage in choke plug 209 and passage 210, the piston chamber 206 is consequently open to the atmosphere. With the piston chamber 206 at atmospheric pressure, the spring 204 acts to hold the piston in seating engagement with the gasket 205. With the piston 202 in this position, the end of the stem 213 thereof will be out of engagement with the contact member 214, so that normally the member 214, due to its inherent spring characteristics, will be held out of contact with the adjacent contact member 215 and as a consequence the circuit through the battery 221 and the magnet 119 is normally maintained open as shown in Fig. 1.

Fluid at feed valve pressure supplied to the slide valve chamber 133 of the application valve device 10 flows therefrom through the restricted passage 136 in the piston 127 to the piston chamber 128. With the pressures in the chambers equalized the spring 130 acts to maintain the piston and the associated slide valve 132 in the inner position as shown in Fig. 1, in which position fluid under pressure flows from valve chamber 133 through passage 164 and passage and pipe 163 to the timing reservoir 14 and diaphragm chamber 162. Fluid under pressure in this chamber 162 acts on the diaphragm to maintain the diaphragm 158 and thereby the follower 159 in its inner position against the opposing pressure of the spring 166, in which position the follower, through the medium of the follower stem 160 and member 61, maintains the double beat valve 150 in its right hand position and maintains the plunger 146 and thereby the valves 137 and 141 in their right hand position, in which position the valve 141 is seated and the valve 137 unseated.

The chamber 138 which contains the valve 137 is constantly connected through passage 139 to the application slide valve chamber 133, so that with the valve 137 unseated the chamber 143 will be charged with fluid at feed valve pressure. With the valve 141 seated fluid under pressure is prevented from leaking to the atmosphere past the collar 147 and stem of the plunger.

With the double beat valve 150 in its right hand position the second reduction reservoir 16 is open to the atmosphere by way of passage 152, valve chamber 151 and past the fluted stem 157 of the valve.

With the piston 127 and slide valve 132 of the application valve device 10 in their inner position, fluid under pressure flows from slide valve chamber 133 through a port 243 in the slide valve, passage 200 and pipe and passage 199 to the piston chamber 198 of the brake valve actuating mechanism 17. Fluid under pressure in this chamber 198 normally maintains the piston 191 in its innermost position against the opposing pressure of the spring 193, in which position the end of the piston stem 192 engages the plunger 224 and maintains the contact member 219 in engagement with the adjacent contact member 220 as shown in Fig. 1.

The 1st reduction reservoir 15 is constantly con-

nected with the atmosphere by way of a pipe 244, a passage 245, a branch passage 246 and the passage in a choke plug 247 having screw-threaded engagement with the brake valve pedestal 2. With the rotary valve 22 of the automatic brake valve device in release position, the passage 245 and consequently the 1st reduction reservoir is connected to the atmosphere by way of a passage 248 in the plug valve 92, a passage 249, a cavity 250 in the rotary valve 22 and an atmospheric passage 251.

With the automatic brake valve device in running position, the cam 27 will be out of operative engagement with the arm 40 so that spring 39 will maintain the valve 32 seated, thus closing communication from the exhaust passage 79 to the atmospheric passage 35. By thus maintaining this communication closed, the possibility of the venting of fluid under pressure from the brake pipe 1 in the event of the piston 70 of the equalizing valve device being unintentionally moved, due to fluctuations in feed valve pressure in piston chamber 96 to unseat the vent valve 78, is entirely eliminated.

If the traffic condition changes from favorable to unfavorable, the magnet 119 is automatically deenergized as is usual, and when deenergized, operates to permit spring 124 to seat valve 122 to close communication from the valve chamber 123 and consequently from the reducing valve to the timing chamber 125 and piston chamber 231, and to unseat the valve 120 to permit fluid under pressure to be vented from the timing chamber 125 and piston chamber 231 by way of passage 126, restricted passage 235, passage 233, chamber 232, past the valve 120, through valve chamber 121 and from thence to the atmosphere through a passage 252 having a restricted vent 253, and at the same time through a pipe 254 and a whistle device 255, the choked passage 235 being adapted to govern the rate of reduction in the pressure in the timing chamber 125 and piston chamber 231, whereas the restricted vent 253 is of less capacity than the restriction in the passage 235 and thereby causes a portion of the fluid under pressure vented from the timing chamber and chamber 231 to flow through the whistle device 255 to cause the same to sound.

When the pressure in the timing chamber 125 and chamber 231 has been thus reduced to a predetermined degree, the spring 110 shifts the valve piston 105 downwardly causing the seat rib 111 to engage the gasket 112 and permitting spring 118 to shift the double beat valve 101 downwardly to its lower seat.

With the double beat valve 101 thus seated in its lower or application position, fluid under pressure is vented from the application piston chamber 128 to the atmosphere through passages and pipe 129, chamber 114, past valve 101, through valve chamber 102 and passage 237, the flow of fluid from the chamber 128 being at a faster rate than that of the flow of fluid from the slide valve chamber 133 to the chamber 128 by way of the restricted port 136 in the piston 127.

When the pressure is thus reduced in the application piston chamber 128, the pressure of fluid in the valve chamber 133 causes the application piston 127 and thereby the slide valve 132 to move outwardly to application position against the opposing pressure of the spring 130.

With the slide valve 132 in its outer or application position, a cavity 256 in said valve connects the passage 200 to an atmospheric passage 257 thereby venting the fluid under pressure

from piston chamber 193 of the brake valve actuating mechanism 17 to the atmosphere at a rapid rate. With the piston chamber 193 thus vented, the spring 193 acts to quickly shift the 5 piston 191 outwardly. As the piston is thus shifted, the arm 195 carried by the stem thereof engages the arm 197 of the brake valve handle 24 and moves said handle and thereby the rotary valve 22 to lap position, in which position 10 said rotary valve laps the charging passage 75 to cut off the supply of fluid under pressure to the equalizing reservoir 12 and piston chamber 96 of the equalizing discharge valve device 5, and laps the supply passage 71 to cut off the supply 15 of fluid under pressure to the brake pipe 1, diaphragm chamber 173 of the suppression valve device 11 and chamber 76 of the equalizing discharge valve device 5. Further, the rotary valve 22 laps the passage 95 thereby cutting off the 20 supply of fluid under pressure to the supply valve chamber 90 of the equalizing discharge valve device 5 and to the passage 167 and pipe 168, and also laps the passages 249 and 251 thereby cutting off the communication from the 1st reduction 25 reservoir to the atmosphere by way of the passage 251.

It will here be noted that in moving from running to lap position, the brake valve handle 24 and rotary valve 22 of the automatic brake 30 valve device must pass through 1st service position, but since this movement will be very rapid, there will be no appreciable reduction effected in the pressure of fluid in either the equalizing reservoir or piston chamber 96 of the equalizing 35 discharge valve device 5, consequently the equalizing discharge valve device will not operate to vent fluid under pressure from the brake pipe by way of the valve 32 which has been unseated by the movement of the cam 27 to lap position. 40 It will thus be understood that such movement of the brake valve handle and rotary valve will not cause an application of the brakes to be effected.

In the application position of the application 45 slide valve 132 the passage and pipe 168 is connected by a cavity 258 in the valve with the passage 144 so that fluid at feed valve pressure flows from the application valve chamber 133 to the supply valve chamber 90 of the equalizing discharge valve device by way of passage 139, maintaining cut-off valve chamber 138, past the open 50 valve 137 and fluted stem 142, through chamber 143, passage 144, cavity 258, passage and pipe 168, passage 167 and passage 91.

55 Further, with the application slide valve 132 in application position a cavity 259 therein connects a passage 260, which is in communication with the equalizing reservoir pipe 13, to a passage 261 which is in communication with the 1st reduction reservoir pipe 244, said passage 60 261 being restricted as indicated by the reference character 262. With this communication established, fluid under pressure is vented from the equalizing reservoir 12 and piston chamber 96 of the equalizing discharge valve device to the 65 1st reduction reservoir 15 at a service rate, the restriction 262 governing said rate. When the equalizing piston chamber pressure is reduced due to such venting, the pressure of fluid in 70 chamber 76 causes the piston 70 to move outwardly. The piston as it thus moves causes the bell crank lever to be actuated to unseat the vent valve 78. With the valve 78 unseated fluid under pressure flows from the chamber 76 and connected brake pipe 1 to the atmosphere by way 75

of passage 79, valve chamber 31 in the cover section of the automatic brake valve casing, past the unseated valve 32 and its fluted stem 33, recess 35 and the flow restricting passage in the choke plug 36.

When the equalizing reservoir pressure equalizes into the 1st reduction reservoir, fluid under pressure flows from said reservoir and equalizing piston chamber 96 to the atmosphere by way of passage 246 and the restricting passage in the 10 choke plug 247, said reservoirs and chamber 96 being connected to the passage 246 as will be understood from the foregoing description. The flow area of the passage in the choke plug 247 is such that after the equalization of the equalizing reservoir pressure into the 1st reduction reservoir the continued reduction in the pressure of fluid in the equalizing reservoir and piston chamber 96 in the equalizing discharge valve device will be at a slower rate. Now when the pressure of fluid 20 in chamber 76 of the equalizing discharge valve device and consequently in the brake pipe 1 is reduced, by the flow of fluid past the open exhaust valve 78, to substantially the pressure of fluid in chamber 96 or to a degree slightly less than 25 the piston chamber pressure, the piston 70 will be caused to move inwardly, said piston actuating the bell crank lever associated therewith to permit the valve 78 to be moved by the spring 83 toward its seat, thus reducing the rate of reduction in the pressure of fluid in the chamber 76 and brake pipe 1. When the rate of reduction in the pressure of fluid in chamber 76 becomes equal to the rate of reduction in the pressure of fluid in the piston chamber 96, the piston 70 and consequently the valve 78 will come 30 to a stop so that the reduction in the pressure of fluid in chamber 76 and the brake pipe 1 will continue at a rate corresponding to the rate of reduction of fluid pressure in piston chamber 40 96 and equalizing reservoir 12 by way of the flow restricting passage in the choke plug 247.

If, due to brake pipe leakage, the pressure of fluid in chamber 76 should be caused to reduce at a faster rate than that at which the pressure 45 of fluid in piston chamber 96 is being reduced by the flow of fluid from the reduction reservoir 15 and equalizing reservoir 12 through the flow restricting passage in the choke plug 247, fluid at the higher pressure in chamber 96 will cause 50 piston 70 to move inwardly. As the piston is thus moved, the stem 71 thereof causes the bell crank lever to rock on the pin 84 in a clockwise direction. When so rocked, the arm 86 of the lever permits the valve 78 to be seated, thus cutting off the exhaust of fluid from the chamber 76 and brake pipe 1. After the valve 78 is seated, the arm 87 of the lever engages the stem of the valve 89 and through the medium of the stem unseats the valve, so that fluid at feed valve 60 pressure now flows from the chamber 90 to the chamber 76 and from thence flows to the brake pipe 1. By thus supplying fluid under pressure to the brake pipe, the brake pipe pressure will not be permitted to reduce at a faster rate than 65 that at which the equalizing reservoir is being reduced by way of the flow restricting passage in the choke plug 247.

When, after the valve 89 has been unseated, the brake pipe pressure in chamber 76 of the 70 equalizing discharge valve device becomes slightly greater than the equalizing reservoir pressure in piston chamber 96, fluid at the higher pressure in chamber 76 causes the piston 70 to move outwardly, causing the bell crank lever, contained in 75

chamber 76, to rock on the pin 84 in a counter-clockwise direction, and as the lever is thus moved the spring 93 causes the valve 89 to seat and cut off the flow of fluid from the chamber 90 to the chamber 76 and brake pipe 1. If, after the valve 89 is seated the piston 70 continues to move outwardly, the bell crank lever will be operated to unseat the valve 78 to vent fluid under pressure from the chamber 76 and brake pipe 1.

From the foregoing description it will be seen that in effecting the first reduction in brake pipe pressure the initial reduction will first be at a fast rate after which the reduction will be at a slow rate. Due to the operation of the equalizing discharge valve device 5 to supply fluid under pressure to the brake pipe in the event of leakage of fluid from the brake pipe, the brake pipe pressure will not be permitted to reduce at a faster rate than that of the reduction in equalizing reservoir pressure as controlled by the flow of fluid through the flow restricting passage of the choke plug 247 to the atmosphere. By thus maintaining brake pipe pressure against leakage it will be understood that a more uniform reduction in brake pipe pressure and consequently a more uniform brake cylinder pressure will be realized on all of the units of a train than would be the case if brake pipe leakage should be permitted to cause an excessive brake pipe gradient. It will be further noted that the first reduction in brake pipe pressure is so controlled that an application of the brakes will be effected in such a manner that the slack in the train will gather or close gently.

Further, with the application slide valve 132 in application position, a cavity 263 therein connects the passage 164 to a passage 264 leading to the atmosphere, said passage being restricted as indicated by the reference character 265. Since the passage 164 is in communication with the passage 163, fluid under pressure is vented from the diaphragm chamber 162 and timing reservoir 14 to the atmosphere at a rate governed by the restriction 265 in the passage 264. Now when the pressure of fluid in the timing reservoir 14 and consequently in the diaphragm chamber 162 has been reduced to a degree below the pressure of the spring 166, the flexible diaphragm 158, follower 159, follower stem 160 and crosshead 161 will be moved, by the action of said spring, in a direction toward the left hand from the position in which it is shown in Fig. 1, permitting the spring 140 to act to seat the maintaining cut-out valve 137 and to unseat the valve 141, and also permitting the spring 156 to act to move the double beat reduction cut-in valve 150 to its left hand seated position in which the atmospheric communication from the valve chamber 151 and consequently from the 2nd reduction reservoir 16 to the atmosphere is closed and in which position the valve chamber 151 is in open communication with the chamber 155.

In the present embodiment of the invention, with the chambers 155 and 151 connected together as just described, the pressure of fluid in the 1st reduction reservoir 15 will quickly equalize into the 2nd reduction reservoir 16 by way of pipe 244, passage 261, a passage 266, chamber 155, past the fluted stem 154, through valve chamber 151 and passage 152. With the passage 260 leading from the equalizing reservoir pipe 73, connected by the cavity 259 in the application slide valve 132 to the passage 261, fluid under pressure flows from the equalizing reservoir to the 1st and 2nd reduction reservoirs 15 and 16 respec-

tively at a service rate as governed by the flow area of the restriction 262 in the passage 261. The consequent reduction in equalizing reservoir pressure causes the equalizing discharge valve device 5 to operate to vent fluid under pressure from the brake pipe. The reduction in equalizing reservoir pressure at the service rate is sufficient to cause the equalizing discharge valve device to operate to effect a full service reduction in brake pipe pressure, so that a full service application of the train brakes will be effected.

The volume of the timing reservoir 14 and the flow area of the restricted passage 265 are so proportioned that it will require from twenty to thirty seconds for the pressure in the reservoir and consequently in the diaphragm chamber 162 to reduce sufficiently to permit the spring 166 to shift the diaphragm 158, follower 159, follower stem 160 and crosshead 161 from the position in which they are shown in Fig. 1 to their outer or second reduction position. It will be understood from the foregoing description that during this delay period the brakes have been applied in such a manner as to gently close or gather the slack in the train. When, due to the outward movement of the follower 159, the second reduction cut-in valve 150 is moved to its cut-in position the braking force on the vehicles of the train will be increased at a more rapid rate than when the parts are in the first reduction position, but since the slack will have been closed or gathered during the initial application of the brakes this increased rate of application cannot cause harsh shocks.

If, after a train control application of the brakes is effected, the track condition becomes favorable, then the magnet 119 becomes energized again and as a result operates to seat valve 120 and unseat valve 122. With valve 122 unseated, fluid under pressure again flows from the reducing valve device 7 to the timing reservoir 125, thereby charging said reservoir. When the pressure in said reservoir becomes sufficient to overcome the pressure of spring 110, the valve piston 105 is operated to seat the double beat valve 101 in its upper position, as shown in Fig. 1, and thereby close communication from the application piston chamber 128 to the atmosphere.

Fluid at feed valve pressure continues to flow from the application valve chamber 133 through port 136 in the application piston 127 to the application piston chamber 128 and when, due to such flow, the pressure of fluid in chamber 128 becomes substantially equal to the pressure of fluid in chamber 133, the spring 130 acts to shift the piston 127 and associated slide valve 132 to their inner or normal release position, in which position they are shown in Fig. 1.

With the application slide valve in its inner position as shown in Fig. 1, fluid at feed valve pressure is again supplied to the piston chamber 193 of the automatic brake valve actuating device causing the piston 191 of said device to move to its innermost position against the opposing pressure of the spring 192, said piston as it is thus moved actuating the plunger 224 to cause the contact member 219 to engage the contact member 220. Fluid at feed valve pressure is also again supplied from the valve chamber 133 to the timing reservoir 14 and diaphragm chamber 162. Fluid under pressure supplied to the chamber 162 causes the diaphragm 158, follower 159, follower stem 160 and crosshead 161 to move toward the right hand against the opposing pressure of the spring 166. This movement of the crosshead 75

causes the valve 141 to be seated and the valve 137 to be unseated and also causes the double beat valve 150 to be moved from its left hand seated position to its right hand seated position. With the double beat valve 150 in its right hand seated position, fluid under pressure is vented from the 2nd reduction reservoir 16 to the atmosphere by way of passage 152, double beat valve chamber 151 and past the fluted stem 157 of the valve.

When the piston 194 is moved to its inner position, the arm 195 carried thereby is out of engagement with the arm 197 of the brake valve handle 24, so that said handle and thereby the rotary valve 22 can be moved by the operator to running position, in which position the brake pipe 1, chamber 76 of the equalizing discharge valve device 5, equalizing reservoir 12 and piston chamber 96 of the equalizing discharge valve device are recharged with fluid at feed valve pressure supplied in the manner hereinbefore described. Fluid under pressure supplied to the brake pipe 1 causes the brakes on the train to release in the usual manner.

In Fig. 10 a modification of a portion of the brake application valve device 10 is illustrated in which, instead of using a 2nd reduction reservoir to provide for a full service reduction in brake pipe pressure, a valve 270 is employed which is subject on one side to the pressure of a spring 271 and which is adapted to permit fluid under pressure to flow from the equalizing reservoir to the atmosphere by way of a passage 272 in a cap nut which holds the spring 271 in the casing and in engagement with the back face of the valve. The spring 271 is of such value that, when the reduction in equalizing reservoir pressure is sufficient to cause a full service reduction in brake pipe pressure to be effected at a service rate, it will act to seat the valve. It will thus be seen that this arrangement will serve the same purpose as the 2nd reduction reservoir 16.

If, when the track conditions change from favorable to unfavorable, the operator observes the signal produced by the whistle 255 and promptly moves the brake valve handle 24 and thereby the rotary valve 22 in the usual manner to effect an application of the brakes, a train control application of the brakes will be prevented as will be apparent from the following description.

When the operator hears the signal produced by the whistle, if he desires to make a split or two stage reduction in brake pipe pressure, he first moves the brake valve handle and thereby the rotary valve 22 either to 1st service position or to service position and then moves these parts from either of the service positions to lap position and finally moves them to service position. If, when the operator hears the signal produced by the whistle, he desires to make a straight-away full service reduction in brake pipe pressure, he promptly moves the brake valve handle 24 and rotary valve 22 through 1st service position and lap position to service position.

Assuming that the rotary valve 22 has been moved from running position to 1st service position as shown in Fig. 6, in which a cavity 280 in the rotary valve connects the passages 15 and 249 together and in which a port 281 establishes communication from the rotary valve chamber 70 to the passage 95 leading to the maintaining valve chamber 96 of the equalizing discharge valve device 5, fluid under pressure now flows from the equalizing reservoir 12 and connected piston chamber 96 of the equalizing discharge valve device to the 1st reduction reservoir 15 by way of

passage 75, cavity 280 in the rotary valve, passage 249, passage 248 in the plug valve 92, passage 245 and pipe 244. Upon equalization of the equalizing reservoir pressure into the 1st reduction reservoir the reduction in equalizing reservoir pressure and consequently in the piston chamber 96 of the equalizing valve device continues at a slow rate due to the flow of fluid from the passage 245 to the atmosphere by way of passage 246 and the flow restricting passage in the choke plug 247.

Upon thus reducing the pressure of fluid in the piston chamber 96, the piston 70 of the equalizing discharge valve device moves upwardly causing the bell crank lever connected with the piston stem 71 to operate to unseat the discharge valve 78 and thereby vent fluid under pressure from the brake pipe 1 to the atmosphere by way of passage 242, passage 240 in the plug valve 241, passage 77, chamber 76 of the equalizing discharge valve device, past the valve 78, through passage 79, past the valve 32 which in the 1st service position is maintained unseated, through recess 35 and atmospheric choke 36, and is also vented to the atmosphere by way of pipe 37 which is in communication with the recess 35, a check valve device 282, pipe 207, passage 208 in the suppression valve device 11, the flow restricting passage in the choke plug 209, passage 210, valve chamber 179, past the fluted stem 182 of the double beat valve 178, through chamber 180 and atmospheric passage 181. The flow of fluid from the brake pipe to the recess 35 is at a faster rate than fluid is permitted to flow from said recess by way of the choke plugs 36 and 209 and as a consequence the pressure of fluid in pipe 207 and piston chamber 206 will be increased and cause the piston 202 to move inwardly against the opposing pressure of the spring 204 from the position in which it is shown in Fig. 1. When the piston 202 is thus moved, the stem thereof engages the insulation on the contact member 214 and flexes the member into contact with the adjacent contact member 215. This closes an electric circuit through the battery 221 and the magnet 119 and the flow of current through this circuit reenergizes the magnet. Upon the reenergization of the magnet in the manner just described, the valve 120 is caused to seat and cut off the flow of fluid from the timing reservoir 125 and the valve 122 is caused to be unseated permitting fluid at reducing valve pressure to be again supplied to the timing reservoir 125.

It will be noted that fluid under pressure supplied to the pipe 207 also flows through a flow restricting passage 283 in a ball check valve device 284 and a passage and pipe 285 to the timing reservoir 13. Since the timing reservoir is thus charged the piston 202 will be held in its inner position for a predetermined period of time of sufficient duration to permit the operator to make a split reduction in brake pipe pressure without permitting the train control apparatus taking over the control of the application.

If the rotary valve 22 is left in 1st service position until such time as the pressure of the fluid in the piston chamber 206 has been reduced by the flow of fluid to the atmosphere through the choke plug 209 to a lower value than that of the compressed spring 204, said spring acts to move the piston 202 to its outer position permitting the contact member 214 to move out of contact with the contact member 215 thus opening the circuit through the battery 221 and magnet 119 and thereby deenergizing the magnet.

Now when the whistle 255 sounds the operator will know that he must promptly move the rotary valve 22 to service position or else the train control apparatus will take over the control of the 5 application of the brakes.

With the rotary valve 22 in service position, a restricted cavity 286 connects the passage 75 to the atmospheric passage 251 so that fluid under 10 pressure is vented from the equalizing reservoir 12 and piston chamber 96 of the equalizing discharge valve device 5 at a service rate as governed by the flow area of the cavity 286.

Upon thus reducing the pressure of fluid in the piston chamber 96 the piston 70 of the equalizing 15 discharge valve device is caused to move upwardly causing the bell crank associated with the piston stem 71 to operate to unseat the valve 78. With the valve 78 unseated fluid under pressure is vented from the brake pipe to the atmosphere and 20 to the piston chamber 206 and timing reservoir 13. Fluid under pressure supplied to the piston chamber 206 causes the piston 202 to move inwardly and said piston, when it is so moved, causes the contact member 214 to contact with 25 the contact member 215 and thereby close the circuit through the battery 221 and magnet 119. The flow of current through the circuit reenergizes the magnet 119 so that it causes the valve 120 to be seated and the valve 122 unseated and 30 as a result the several parts of the timing valve mechanism 9 will remain in the positions in which they are shown in Fig. 1 and consequently the train control apparatus will have no control over the application of the brakes.

Now when substantially a full service reduction in brake pipe pressure has been effected, fluid at 35 feed valve pressure in chamber 171 of the suppression valve device causes the diaphragm 170 to flex in a direction toward the left hand compressing the spring 176 and, through the medium of the follower 175 and follower stem 177, shifting the double beat valve 178 to its left hand seated position against the opposing pressure of the spring 184. With the valve in this position, the 40 atmospheric communication from the double beat valve chamber 179 and consequently from the piston chamber 206 and timing reservoir 13 is closed. Further, with the double beat valve in this position fluid at brake pipe pressure flows 45 from chamber 173 of the suppression valve past the fluted stem 177 of the double beat valve to the chamber 179 and from thence flows to the pipe 207 and consequently to the piston chamber 206 and timing reservoir 13. Thus, when a full service 50 reduction in brake pipe pressure has been effected the pressure of fluid in piston chamber 206 is maintained from the brake pipe, and since the exhaust communication from the chamber 179 is closed, the operator may now move the rotary 55 valve to lap position and may maintain it in this position as long as he desires without causing the train control apparatus to move to application position.

If the operator, when he hears the signal 60 whistle 255, moves the brake valve handle 24 and thereby the rotary valve 22 to service position, then to lap and finally to service position to effect a split reduction in brake pipe pressure the train control apparatus will be prevented from operating to application position, provided the rotary valve 22 is not maintained in lap position too long, all of which will be understood from the foregoing description. It will also be understood that if the operator moves the rotary valve 22 to service 65 position and maintains it in this position un-

til a full service reduction in brake pipe pressure is effected, the train control apparatus will not operate to its brake application position.

If, when the track conditions are still unfavorable, the operator should move the rotary valve to 5 release position, the train control apparatus will be set in operation to maintain the brakes applied.

It will be noted that at any time, regardless of whether or not the train control apparatus has 10 operated to effect an application of the brakes, the operator may cause an emergency application of the brakes, for when the rotary valve 22 is moved to emergency position, as shown in Fig. 9, a cavity 287 in the valve connects the passage 75 15 leading from the equalizing reservoir 12 and piston chamber 96 of the equalizing discharge valve device 5 and the passage 77 leading from the brake pipe 1 to the atmospheric passage 251, so that a sudden reduction in brake pipe pressure 20 will be effected regardless of the position the train control apparatus may be in.

In Figs. 11, 12 and 13 a modification of the invention is illustrated which differs from the form of the invention shown in Figs. 1 to 9 mainly in 25 that the means employed for suppressing a train control application of the brakes is controlled pneumatically instead of electrically.

In this form of the invention the casing of the 30 brake valve actuating mechanism 17 is provided with a chamber 300 containing a cylinder casing 301 in which there is slidably mounted a piston 302 having a stem 303 which extends through an opening in the cylinder casing and which, at its outer end, is operatively connected to a lever 304 35 pivoted at one end to the cylinder casing 190. The piston chamber at the face side of the piston 302 is connected to the passage and pipe 207. The chamber at the back side of the piston contains a spring 305 which, at all times, tends to move the 40 piston 302 to its normal position, as shown in Fig. 11.

The outer end of the lever 304 has operatively connected thereto a plunger rod 306 which is secured to one end of a slide valve 307 contained in 45 a chamber 308 in the cylinder casing 190, said chamber 308 being constantly connected through a passage 309 with the atmosphere. The other end of the slide valve is adapted to be operatively engaged by a plunger 310 which is adapted to be 50 operated through the medium of an operating arm 311 with which the rotary valve operating stem 23 is provided, the plunger being provided with an elongated opening 312 for the reception of the arm 311.

With the exceptions just noted the automatic 55 brake valve device and brake valve pedestal are substantially the same as shown in Figs. 1 to 9 inclusive.

The application valve device 10 is substantially 60 the same as the corresponding device shown in Fig. 1, the only difference being that there has been provided in the casing of the device shown in Figs. 11 an additional passage 315, the purpose of which passage will hereinafter be described.

The timing valve mechanism 9 is identical with the corresponding mechanism shown in Fig. 1.

The apparatus shown in Fig. 11, besides comprising the above mentioned devices and mechanism 70 also comprises a brake application suppression valve device 320 and a brake pipe reduction ensuring valve device 321.

The brake application suppression valve device 320 comprises a casing having a flexible dia- 75

phragm 322 mounted therein. At one side of the diaphragm there is a chamber 323 which, with the slide valve 307 in its normal position, as shown in Fig. 11, is connected through passages and pipe 324, valve chamber 308 and passage 309 to the atmosphere. At the other side of the diaphragm is a chamber 325 which, with the application valve device 10 in its normal position as shown, is connected to the atmosphere by way of a passage and pipe 326, passage 315, cavity 256 in the application slide valve 132 and passage 257. Contained in the chamber 325 and operatively associated with the flexible diaphragm 322 is a follower member 327 which is subject to the pressure of a spring 328 also contained in the chamber 325. The follower member is provided with a stem 329 which is adapted to engage a fluted stem 330 of a double beat valve 331 contained in a chamber 332 which is constantly connected through a passage 333 with the atmosphere. Projecting from the other side of this double beat valve and extending into a chamber 334 which is constantly connected through a passage and pipe 335 to the exhaust passage 237 of the timing mechanism 9, is a fluted stem 336 which is operatively engaged by one end of a plunger 337 which is slidably mounted in the casing. Interposed between and operatively engaging the plunger 337 and the casing is a spring 338 which, at all times, tends to urge the plunger 337 and thereby the double beat valve 331 in a direction toward the right hand.

The brake pipe reduction ensuring valve device 321 comprises a casing having a flexible diaphragm 340 mounted therein. At one side of the diaphragm there is a chamber 341 which is connected through a passage 342 to the feed valve pipe 134. At the other side of the diaphragm there is a chamber 343 which is connected through a passage 344 to the brake pipe 1. Contained in the chamber 343 and operatively associated with the flexible diaphragm 340 is a follower member 344 which is subject to the pressure of a spring 345 also contained in the chamber 343. The follower member is provided with a stem 346 which is adapted to engage a fluted stem 347 projecting from the right hand side of a double beat valve 348 contained in a chamber 349 which is constantly connected to the pipe 207 through a passage 350, a flow restricting passage in a choke plug 351 and a passage 352. Projecting from the other side of the double beat valve 348 and extending into a chamber 353 which is constantly connected through a passage 354 with the atmosphere is a fluted stem 355 which is operatively engaged by one end of a plunger 356 slidably mounted in the casing. Interposed between and operatively engaging the plunger 356 and the casing is a spring 357 which, at all times, tends to urge the plunger and thereby the double beat valve 348 in a direction toward the right hand.

With the equipment charged with fluid under pressure in the manner hereinbefore described in connection with the equipment shown in Fig. 1, the several parts of the equipment shown in Fig. 11 will be in the positions in which they are shown.

Since the pressure of fluid in chambers 341 and 343 of the brake pipe reduction ensuring valve device 321 are substantially equal, the spring 345 acts to hold the follower member 344 and thereby the flexible diaphragm 340 in their extreme right hand position, in which position the plunger 356, under the influence of the spring 357, holds the double beat valve 348 in its right hand seated position. With the double beat valve in this position

the pipe 207 and consequently the piston chamber at one side of the piston 302 is connected with the atmosphere by way of passage 352, the flow restricting passage in the choke plug 351, passage 350, valve chamber 349, past the fluted stem 355 of the rouble beat valve 348, through chamber 353 and passage 354.

The chambers 323 and 325 of the brake application suppression valve device 320 being at atmospheric pressure, the spring 328 acts to hold the follower member 327 and diaphragm 322 in their extreme right hand position, in which position, the plunger 337, under the influence of the spring 338, holds the double beat valve 331 in its right hand seated position. With the double beat valve 331 in this position the exhaust passage 237 of the timing valve mechanism 9 is connected to the atmosphere by way of pipe and passage 335, chamber 334, past the fluted stem 336 of the double beat valve 331, through valve chamber 332 and passage 333.

If, with the automatic brake valve device of the apparatus shown in Fig. 11 in running position, the traffic conditions change from favorable to unfavorable, the magnet 119 is deenergized so that the timing valve mechanism 9 and application valve device are caused to function to effect a split or two stage reduction in brake pipe pressure and thereby cause a full service application of the brakes. It will be understood that the operation of the timing valve mechanism and application valve device to effect an application of the brakes is substantially the same as has been fully described in connection with the apparatus shown in Fig. 1, and in view of this a detailed description here of the operation of the apparatus is deemed unnecessary.

When the track conditions change from unfavorable to favorable, the several parts of the train control apparatus will be automatically returned to their normal positions, as shown in Fig. 11, and the operator will return the brake valve handle 24 to running position and the brakes will be released, all of which is accomplished in substantially the same manner as described in connection with the apparatus shown in Fig. 1.

If, when the traffic conditions change from favorable to unfavorable, the operator acts promptly, upon hearing the signal produced by the whistle 255, to move the brake valve handle 24 and thereby the rotary valve 22 to effect a full service application of the brakes within a predetermined time, a train control application of the brakes will be prevented. 55

When the operator hears the signal produced by the whistle, if he desires to make a split or two stage reduction in brake pipe pressure he may first move the brake valve handle 24 and thereby the rotary valve 22 from running position to 1st service position or to service position, then to lap and finally to service position.

It will be understood that when the rotary valve is in either service position, fluid vented from the brake pipe, through the operation of the equalizing discharge valve device 5, is supplied to the pipe 207 in the same manner as described in connection with the apparatus shown in Fig. 1. Fluid under pressure thus supplied to the pipe 207 flows to the timing reservoir 13 and to the piston chamber at the face side of the piston 302. Fluid under pressure thus supplied to the piston chamber causes the piston to move outwardly against the opposing pressure 75

- of the spring 305 and through the medium of the piston stem 303 actuates the lever 304 to shift the slide valve in a direction toward the left hand to a position in which a cavity 360 5 connects a passage 361, leading from the piston chamber 198, to the passage 324. With this communication established fluid under pressure flows from said piston chamber to the diaphragm chamber 323 of the suppression valve device 320.
- 10 When the pressure of fluid in chamber 323 and acting on the diaphragm 322 becomes high enough to overcome the opposing pressure of the spring 345 the diaphragm acts to move the follower member 327 in a direction toward the left hand. When the follower is thus moved, the stem 329 thereof engages the end of the fluted stem 330 of the double beat valve 331 and shifts said valve from its right hand seated position to its left hand seated position. The double beat 15 valve in this position closes the atmospheric communication from the exhaust passage 237 of the timing valve mechanism 9, so that when the double beat valve moves downwardly and establishes communication from the passage 129 20 and consequently from the application piston chamber 128 to the passage 237, fluid under pressure will not be permitted to flow to the atmosphere and the application piston will remain in its normal position.
- 25 When the desired reduction in brake pipe pressure is effected, the operator moves the brake valve handle 24 and thereby the rotary valve 22 to lap position and then moves the handle and rotary valve to service position and maintains the handle and valve in service position 30 until a full service reduction in brake pipe pressure has been effected after which the handle and valve may be moved to lap position.

It will be noted that after the first reduction in brake pipe pressure has been completed 40 by moving the rotary valve 22 to lap position the pressure of fluid in the timing reservoir 13 and piston chamber at the face side of the piston 302 reduces due to the flow of fluid therefrom by way of pipe 207, passage 352, flow restricting passage in the choke plug 351, passage 350, valve chamber 349, past the fluted valve stem 355, through chamber 353 and passage 354. The volume of the reservoir 13 and the flow area of the restricting passage in the choke 45 plug 351 are so proportioned with relation to each other that it will require several seconds for the timing reservoir pressure to reduce sufficiently to permit the spring 305 to return the piston 302 and thereby the slide valve 307 to 50 their normal position.

If the operator moves the rotary valve 22 from lap to service position before the slide valve 307 is returned to its normal position, fluid under pressure is again supplied to the pipe 207 and 55 consequently to the timing reservoir and as a result the piston 302 will be maintained in its outer position and the slide valve 307 will remain in the position to which it has been moved by the piston 302. Now, if the operator leaves 60 the rotary valve 22 in service position until a full service reduction in brake pipe pressure has been effected, fluid at feed valve pressure in diaphragm chamber 341 of the reduction insuring valve device 321 causes the diaphragm and associated follower member 344 to move in a direction 65 toward the left hand against the opposing pressure of the brake pipe and spring 345 in chamber 343. The follower member as it is thus moved engages the fluted stem 347 of the double beat valve 348 and shifts said valve to its 70 75

left hand position, in which position it cuts off the exhaust of fluid under pressure from the timing reservoir 13 and at the same time permits fluid at brake pipe pressure to flow from diaphragm chamber 343 to said reservoir and the piston chamber at the face side of the piston 302, past the fluted valve stem 347, through chamber 349, passage 350, flow restricting passage in the choke plug 351, passage 352 and pipe 207. It will here be noted that when the brake 10 valve handle 24 is moved from lap to service position the arm 311 on the operating stem 23 of the rotary valve causes the plunger 310 to move in a direction toward the left hand a sufficient distance to shift the slide valve 307 to its forward position if the piston 302 has not already been operated to do so. This plunger also serves to positively maintain the slide valve 307 in its forward position as long as the brake valve handle is in service position.

If the operator should leave the rotary valve 22 too long in lap position after the first reduction in brake pipe pressure has been effected, that is to say, until the pressure of fluid in the timing reservoir 13 and piston chamber at the face side 25 of the piston 302 has been reduced below the value of the spring 305, said spring acts to move the piston and thereby the slide valve 307 to normal position. With the slide valve in this position the communication between the passages 361 30 and 324 is cut off and the passage 324 is connected to the slide valve chamber 308 which is open through passage 309 to the atmosphere. Since the passage 324 is in communication with the diaphragm chamber 323 of the suppression 35 valve device 320, fluid under pressure is vented from said chamber 323 to the atmosphere. With chamber 323 vented, the spring 328 causes the follower member 327 and follower to move in a direction toward the right hand permitting the plunger 337, acting under the influence of the spring 338, to shift the double beat valve 331 to its right hand seated position, in which the chamber 334 and consequently the exhaust passage 237 of the timing valve mechanism 9 is open to the atmosphere by way of the fluted stem 330 40 of the double beat valve, valve chamber 332 and passage 333. By this time the pressure of fluid in the timing reservoir 125 of the timing valve mechanism 9 will have been reduced sufficiently 45 to permit the valve piston to be moved to its lower seated position in which the double beat valve 101 will be in its lower seated position in which the passage 129 is open to the exhaust passage 237. Since the passage 129 is in communication with the application piston chamber 128, fluid under pressure is now vented from said 50 chamber to the atmosphere.

Upon the venting of fluid under pressure from the application piston chamber 128 the application valve device is caused to operate to effect a train control application of the brakes. It will be noted that, when in effecting such an application, the piston chamber 198 of the brake valve actuating device 17 is vented and the piston 191 60 is moved forwardly, said piston closes the passage 361 to the chamber 198, so that if the operator should move the rotary valve 22 to service position the train control application cannot be suppressed.

Furthermore, even if the operator attempts such suppression before piston 191 laps the passage 361, but after the application piston 127 has moved to lap position, the opening of passage 315 to valve chamber 133 permits supply of fluid through 70 75

pipe 326 to diaphragm chamber 325 of the suppression valve device 320 which acts to maintain the suppression valve device in the position for effecting a train control application of the brakes 5 regardless of the pressure of fluid which may be obtained in chamber 323 due to the operation of the brake valve device.

When traffic conditions change from unfavorable to favorable either a train control application 10 of the brakes or a manual application of the brakes will be released in substantially the same manner as has been described in connection with the apparatus shown in Fig. 1.

While several illustrative embodiments of the 15 invention have been described in detail, it is not the intention to limit its scope to these embodiments or otherwise than by the terms of the appended claims.

Having now described our invention, what we 20 claim as new and desire to secure by Letters Patent, is:

1. In a train control brake equipment, in combination, a brake pipe, a brake valve device having a normal position for supplying fluid under 25 pressure to said brake pipe, a lap position for cutting off the supply of fluid under pressure to said brake pipe and an application position for venting fluid under pressure from said brake pipe, a handle operable manually to move said brake 30 valve device out of said normal position to either said lap or application position, a movable abutment, a lug associated with said abutment and operative by said abutment to effect movement of said handle and thereby said brake valve device 35 out of said normal position to lap position only, and means operative upon a change in signal indication to effect operation of said abutment, the movement of said brake valve device by said handle being independent of said abutment.

40 2. In a train control brake equipment, in combination, a brake pipe, a brake valve device having a normal position in which fluid under pressure is supplied to the brake pipe and operative manually to effect a reduction in brake pipe pressure and movable either manually or automatically to a lap position for cutting off the supply of fluid under pressure to the brake pipe, means for effecting the automatic movement of said brake valve device to lap position, mechanism operative 45 automatically to effect a reduction in brake pipe pressure, control means operative upon a change in signal indication to effect the operation of said means and said mechanism, and means controlled by the first mentioned means for preventing the 50 operation of said control means upon operation of said brake valve device manually.

3. In a train control brake equipment, in combination, a brake pipe, a brake valve device having a normal position in which fluid under pressure 55 is supplied to the brake pipe and operative manually to effect a reduction in brake pipe pressure and movable either manually or automatically to a lap position for cutting off the supply of fluid under pressure to the brake pipe, means for effecting the automatic movement of said brake valve device to lap position, mechanism operative automatically to effect a reduction in brake pipe pressure, control means operative upon a change in signal indication to effect the 60 operation of said means and said mechanism, and means operated upon movement of the brake valve device to a brake applying position for suppressing the operation of the control means.

4. In a train control brake equipment, in combination, a brake pipe, a brake valve device hav-

ing a normal position in which fluid under pressure is supplied to the brake pipe and operative manually to effect a reduction in brake pipe pressure and movable either manually or automatically to a lap position for cutting off the supply 5 of fluid under pressure to the brake pipe, a movable abutment having a normal position and movable therefrom to effect movement of said brake valve device to said lap position, control means operative upon a change in signal indication for effecting the operation of said movable abutment, suppression means associated with said abutment, and means conditioned upon operation of said brake valve device, to effect a reduction in brake pipe pressure, to cooperate 10 with said suppression means when said abutment is in the normal position to prevent the operation of said movable abutment upon a change in signal indication.

5. In a train control brake equipment, in combination, a brake pipe, a brake valve device having a normal position in which fluid under pressure is supplied to the brake pipe and operative manually to effect a reduction in brake pipe pressure and movable either manually or automatically to a lap position for cutting off the supply of fluid under pressure to the brake pipe, a movable abutment having a normal position and movable therefrom to effect movement of said brake valve device to said lap position, control means operative upon a change in signal indication for effecting the operation of said movable abutment, means operative to render said control means ineffective to effect the operation of said abutment, said brake valve device 35 being operative, when moved manually to effect a reduction in brake pipe pressure, to effect the operation of said means.

6. In a train control brake equipment, in combination, a brake pipe, a brake valve device having a normal position in which fluid under pressure is supplied to the brake pipe and operative manually to effect a reduction in brake pipe pressure and movable either manually or automatically to a lap position for cutting off the supply 45 of fluid under pressure to the brake pipe, a movable abutment having a normal position and movable therefrom to effect movement of said brake valve device to said lap position, control means operative upon a change in signal indication for effecting the operation of said movable abutment, means operative to render said control means ineffective to effect the operation of said abutment, said brake valve device being operative, when moved manually to effect a reduction 50 in brake pipe pressure, to effect the operation of said means, and means operative after effecting a full service reduction in brake pipe pressure and with the brake valve device in said lap position to effect the operation of said means.

7. In a train control brake equipment, in combination, a brake pipe, a brake valve device having a normal position in which fluid under pressure is supplied to the brake pipe and operative manually to effect a reduction in brake pipe pressure and movable either manually or automatically to a lap position for cutting off the supply 65 of fluid under pressure to the brake pipe, a movable abutment having a normal position and movable therefrom to effect movement of said brake valve device to said lap position, control means operative upon a change in signal indication for effecting the operation of said movable abutment, switch means operative to render said control means ineffective to effect the operation 70

of said abutment, said brake valve device being operative when moved manually to effect a reduction in brake pipe pressure to effect the operation of said switch means, and means operative upon obtaining a full service reduction in brake pipe pressure to effect the operation of said switch means.

8. In a train control brake equipment, in combination, a brake pipe, a brake valve device having a normal position in which fluid under pressure is supplied to the brake pipe and operative manually to effect a reduction in brake pipe pressure and movable either manually or automatically to a lap position for cutting off the supply of fluid under pressure to the brake pipe, a movable abutment having a normal position and movable therefrom to effect movement of said brake valve device to said lap position, control means operative upon a change in signal indication for effecting the operation of said movable abutment, valve means operative to render said control means ineffective to effect the operation of said abutment, means for manually operating said brake valve device and operative to operate said valve means upon manual operation of said brake valve device to effect a reduction in brake pipe pressure, and mechanism operative upon a full service reduction in brake pipe pressure for also operating said valve means.

9. In a train control brake equipment, in combination, a brake pipe, a brake valve device having a normal position for supplying fluid under pressure to said brake pipe and movable manually therefrom to an application position for effecting a service reduction in brake pipe pressure, and movable either manually or automatically to a lap position for cutting off the supply of fluid under pressure to said brake pipe, a handle for manually moving said brake valve device to said positions, a fluid pressure controlled abutment having a normal position and movable therefrom to effect movement of said brake valve device to lap position automatically, mechanism operative to effect a reduction in brake pipe pressure, means operative upon a change in signal indication to automatically effect the operation of said abutment and mechanism, and cooperating means associated with said abutment and brake valve device and operative upon manual movement of said handle to said application position and with said abutment in said normal position to prevent the operation of said abutment and mechanism.

10. In a train control brake equipment, in combination, a brake pipe, a brake valve device having a normal position for supplying fluid under pressure to said brake pipe and movable manually therefrom to an application position for effecting a service reduction in brake pipe pressure, and movable either manually or automatically to a lap position for cutting off the supply of fluid under pressure to said brake pipe, a handle for manually moving said brake valve device to said positions, a fluid pressure controlled abutment having a normal position and movable therefrom to effect movement of said brake valve device to lap position automatically, mechanism operative to effect a reduction in brake pipe pressure, a normally energized electro-responsive device adapted to be deenergized upon a change in signal indication for effecting the operation of said abutment and mechanism, a source of electrical energy, a switch controlled by said abutment and closed when said abutment is in said normal position, another switch controlled by said handle

and closed upon operation of said handle to move said brake valve device to application position, said switches being connected in series with each other and said source of electrical energy and said electroresponsive device whereby said electroresponsive device may be energized if the brake valve handle is moved to said application position before movement of said abutment out of said normal position.

11. In a train control brake equipment, in combination, a brake pipe, a brake valve device having a normal position for supplying fluid under pressure to said brake pipe and movable manually therefrom to an application position for effecting a service reduction in brake pipe pressure, and movable either manually or automatically to a lap position for cutting off the supply of fluid under pressure to said brake pipe, a handle for manually moving said brake valve device to said positions, a fluid pressure controlled abutment having a normal position and movable therefrom to effect movement of said brake valve device to lap position automatically, mechanism operative to effect a reduction in brake pipe pressure, a normally energized electro-responsive device adapted to be deenergized upon a change in signal indication for effecting the operation of said abutment and mechanism; a source of electrical energy, a switch controlled by said abutment and closed when said abutment is in said normal position, another switch controlled by said handle and closed upon operation of said handle to move said brake valve device to application position, said switches being connected in series with each other and said source of electrical energy and said electroresponsive device whereby said electroresponsive device may be energized if the brake valve handle is moved to said application position before movement of said abutment out of said normal position, and means operative while fluid under pressure is being vented from the brake pipe for maintaining the second mentioned switch closed upon movement of said handle to lap position.

12. In a train control brake equipment, in combination, a brake pipe, a brake valve device having a normal position for supplying fluid under pressure to said brake pipe and movable manually therefrom to an application position for effecting a service reduction in brake pipe pressure, and movable either manually or automatically to a lap position for cutting off the supply of fluid under pressure to said brake pipe, a handle for manually moving said brake valve device to said positions, a fluid pressure controlled abutment having a normal position and movable therefrom to effect movement of said brake valve device to lap position automatically, mechanism operative to effect a reduction in brake pipe pressure, a normally energized electroresponsive device adapted to be deenergized upon a change in signal indication for effecting the operation of said abutment and mechanism, a source of electrical energy, a switch controlled by said abutment and closed when said abutment is in said normal position, another switch controlled by said handle and closed upon operation of said handle to move said brake valve device to application position, said switches being connected in series with each other and said source of electrical energy and said electroresponsive device whereby said electroresponsive device may be energized if the brake valve handle is moved to said application position before movement of said abutment out of said normal position, and means controlled by

brake pipe pressure and operative upon a full service reduction in brake pipe pressure for maintaining the second mentioned switch closed independently of the brake valve handle.

- 5 13. In a train control brake equipment, in combination, a brake pipe, a brake valve device having a normal position for supplying fluid under pressure to said brake pipe and movable manually therefrom to an application position 10 for effecting a service reduction in brake pipe pressure, and movable either manually or automatically to a lap position for cutting off the supply of fluid under pressure to said brake pipe, a handle for manually moving said brake valve 15 device to said positions, a fluid pressure controlled abutment having a normal position and movable therefrom to effect movement of said brake valve device to lap position automatically, mechanism operative to effect a reduction in 20 brake pipe pressure, a normally energized electroresponsive device adapted to be deenergized upon a change in signal indication for effecting the operation of said abutment and mechanism, a source of electrical energy, a switch controlled 25 by said abutment and closed when said abutment is in said normal position, another switch controlled by said handle and closed upon operation of said handle to move said brake valve device to application position, said switches being 30 connected in series with each other and said source of electrical energy and said electroresponsive device whereby said electroresponsive device may be energized if the brake valve handle is moved to said application position before 35 movement of said abutment out of said normal position, means operative by fluid under pressure vented from the brake pipe for holding the second mentioned switch closed while fluid is being vented from the brake pipe and for a predetermined period of time after such venting ceases and with said handle in lap position, and means operative after effecting a full service 40 reduction in brake pipe pressure for supplying fluid under pressure for effecting operation of the last mentioned means independently of said 45 brake valve handle.
14. In a train control brake equipment, in combination, a brake pipe, a brake valve device having a normal position for supplying fluid under pressure to said brake pipe, a lap position for cutting off the supply of fluid under pressure to said brake pipe and an application position for venting fluid under pressure from said brake pipe, a fluid pressure controlled abutment having 50 a normal position and movable therefrom to move said brake valve device from said normal position to said lap position, a handle for manually moving said brake valve device to all of said positions independently of said abutment, valve 55 means operative to effect a reduction in brake pipe pressure independently of said brake valve device, mechanism operative upon a change in signal indication to automatically effect the operation of said abutment and valve means, a 60 valve device operative to prevent the operation of said valve means, and valve means positioned by said handle upon movement to said application position and cooperative with said abutment in said normal position to effect the operation of 65 said valve device.
- 70 15. In a train control brake equipment, in combination, a brake pipe, a brake valve device having a normal position for supplying fluid under pressure to said brake pipe, a lap position for cutting off the supply of fluid under pressure to 75

said brake pipe and an application position for venting fluid under pressure from said brake pipe, a fluid pressure controlled abutment having a normal position and movable therefrom to move said brake valve device from said normal position to said lap position, a handle for manually moving said brake valve device to all of said positions independently of said abutment, valve means operative to effect a reduction in brake pipe pressure independently of said brake valve device, mechanism operative upon a change in signal indication to automatically effect the operation of said abutment and valve means, a valve device operative to prevent the operation of said valve means, valve means positioned by said handle upon movement to said application position and cooperative with said abutment in said normal position to effect the operation of said valve device, and means operative after obtaining a full service reduction in brake pipe pressure for effecting the operation of said valve device independently of said handle.

16. In a train control brake equipment, in combination, a brake pipe, a brake valve device having a normal position for supplying fluid under pressure to said brake pipe, a lap position for cutting off the supply of fluid under pressure to said brake pipe, and an application position for effecting a reduction in brake pipe pressure, a handle operative manually to move said brake valve device to said positions, traffic controlled means operative automatically upon a change in signal indication to move said brake valve device to said lap position and to effect a reduction in brake pipe pressure, electropneumatic means controlled jointly by said handle and the traffic controlled means and operative to suppress the operation of said traffic controlled means when said brake valve device is manually moved to application position, and means controlled by brake pipe pressure and operative upon obtaining a full service reduction in brake pipe pressure to maintain the electropneumatic means in the suppress ing condition independently of said handle.

17. In a train control brake equipment, the combination with a brake pipe, an equalizing reservoir, a brake pipe discharge valve mechanism controlled by the opposing pressures of said brake pipe and reservoir and operative upon a reduction in equalizing reservoir pressure to effect 50 a corresponding reduction in brake pipe pressure, a reduction reservoir having a restricted atmospheric vent, valve means operative upon a change in signal indication to connect said equalizing reservoir to said reduction reservoir where- 55 by fluid is vented from said equalizing reservoir to said reduction reservoir at a substantially service rate until substantial equalization of pressures in said reservoirs is obtained and then to the atmosphere at a slower rate through said 60 atmospheric vent, means operative to effect another and further reduction in pressure in said equalizing reservoir, timing means set in operation upon initiating the initial reduction in equalizing reservoir pressure for cutting said means 65 into action after a certain time has elapsed from the start of the initial reduction in equalizing reservoir pressure, and means for limiting the total reduction in pressure in said equalizing reservoir to a full service reduction.

18. In a fluid pressure brake, in combination, a brake pipe, an equalizing reservoir, a reduction reservoir having a restricted atmospheric vent, valve means responsive to a reduction in equalizing reservoir pressure to effect a corresponding 75

reduction in brake pipe pressure, a brake valve device movable manually to one position for establishing a communication between said reservoirs through which fluid under pressure flows from said equalizing reservoir to said reduction reservoir at a service rate until substantial equalization of pressures in said reservoirs is obtained and then to the atmosphere through said atmospheric vent at a slower rate, said brake valve device being movable to another position for continuing the reduction in equalizing reservoir pressure at a service rate and finally movable to a lap position for limiting the reduction in equalizing reservoir pressure, traffic controlled means automatically operative upon a change in signal indication to establish a communication between said reservoirs for effecting initially a service reduction and then a slower reduction in equalizing reservoir pressure, and finally operative to initiate a further reduction in equalizing reservoir pressure at a service rate, and timing means set in operation upon the initiation of the operation of the traffic controlled means for delaying the initiation of said further reduction in equalizing reservoir pressure until after a chosen interval of time has elapsed from the initiation of the initial reduction in equalizing reservoir pressure.

19. In a fluid pressure brake, in combination, a brake pipe, an equalizing reservoir, a normally vented reduction reservoir, valve means operative upon a reduction in equalizing reservoir pressure to effect a corresponding reduction in brake pipe pressure, a brake valve device movable manually to one position for establishing communication between said reservoirs through which fluid under pressure in said equalizing reservoir is adapted to reduce at substantially a service rate into said reduction reservoir until substantial equalization of pressures in said reservoirs is obtained, said brake valve device being movable to another position for continuing the reduction in equalizing reservoir pressure at a service rate, and finally movable to a lap position for limiting the reduction in equalizing reservoir pressure, traffic controlled means operative automatically upon a change in signal indication for establishing a communication between said reservoirs, independently of said brake valve device, for effecting an initial reduction in equalizing reservoir pressure at a service rate and then operative to effect a second reduction in equalizing reservoir pressure at a service rate, means set in operation upon said change in signal indication for delaying the operation of said traffic controlled means to initiate said second reduction in equalizing reservoir pressure until after a chosen time interval has elapsed from the initiation of said initial reduction in equalizing reservoir pressure, and means operative automatically to limit the degree of reduction in equalizing reservoir pressure effected by the operation of said traffic controlled means to a full service reduction.

20. In a fluid pressure brake, in combination, a brake pipe, an equalizing reservoir, a discharge valve operative to vent fluid under pressure from said brake pipe, a supply valve operative to supply fluid under pressure to said brake pipe, a movable abutment subject to the opposing pressures of said equalizing reservoir and brake pipe and operative when the equalizing reservoir pressure is lower than brake pipe pressure to operate said discharge valve to vent fluid under pressure from the brake pipe, and operative when brake pipe pressure is lower than equalizing res-

ervoir pressure to operate said supply valve to supply fluid under pressure to the brake pipe, a brake valve device movable to a position for establishing a communication through which fluid under pressure is supplied to said supply valve, and for at the same time venting fluid under pressure from said equalizing reservoir, said brake valve device being movable to a lap position to close said communication and lap said reservoir, valve means operative independently of said brake valve device to establish a communication through which fluid under pressure is supplied to said supply valve and to also vent fluid under pressure from said equalizing reservoir, and means operative upon a change in signal indication to automatically effect the operation of said valve means, and to automatically move said brake valve device to lap position.

21. In a train control equipment, in combination, a brake pipe, an equalizing reservoir, a brake pipe discharge valve, a brake pipe maintaining valve operative to supply fluid under pressure to said brake pipe, a movable abutment subject to the opposing pressures of said brake pipe and equalizing reservoir, and operative upon a reduction in equalizing reservoir pressure to effect the operation of said discharge valve to effect a corresponding reduction in brake pipe pressure, and operative in case brake pipe pressure reduces, due to leakage, faster than equalizing reservoir pressure is reduced, to effect operation of said maintaining valve to supply fluid under pressure to the brake pipe at a rate sufficient to offset such leakage, valve means operative upon a change in signal indication to effect a reduction in equalizing reservoir pressure, control means automatically operative upon the operation of said valve means to divide said reduction in equalizing reservoir pressure into a first stage of reduction and a second stage of reduction, and means controlled by said control means and operative during said first stage of reduction to establish a communication through which fluid under pressure is supplied to said maintaining valve, and operative to cut off such supply of fluid under pressure to said maintaining valve during said second stage of reduction.

22. In a train control equipment, in combination, a brake pipe, a brake valve device operative manually to effect a reduction in pressure in said brake pipe to effect an application of the brakes, and to supply fluid under pressure to said brake pipe to effect a release of the brakes, and movable to a lap position for lapping the brake pipe, an actuator operative automatically to move said brake valve device to said lap position, an application valve device movable to an application position for effecting the operation of said actuator and for automatically effecting a reduction in brake pipe pressure at a service rate, control means set in operation upon movement of said application valve device to application position for controlling the degree of said service rate of reduction in brake pipe pressure and operative during the initial portion of said reduction to establish a communication through which fluid under pressure is adapted to be supplied to the brake pipe, in case of brake pipe leakage, at a rate corresponding to such leakage, means for effecting the operation of said control means to close said communication a chosen time interval after movement of said application valve device to application position, and means responsive to a change in signal indication

adapted to effect movement of said application valve device to said application position.

23. In a train control equipment, in combination, a brake pipe, a brake valve device operative manually to effect a reduction in pressure in said brake pipe to effect an application of the brakes, and to supply fluid under pressure to said brake pipe to effect a release of the brakes, and movable to a lap position for lapping the brake pipe, an actuator operative automatically to move said brake valve device to said lap position, an application valve device movable to an application position for effecting the operation of said actuator and for automatically effecting a reduction in brake pipe pressure at a service rate, control means set in operation upon movement of said application valve device to application position for controlling the degree of service rate of reduction in brake pipe pressure and operative during the initial portion of said reduction to establish a communication through which fluid under pressure is adapted to be supplied to the brake pipe, in case of brake pipe leakage, at a rate corresponding to such leakage, means for effecting the operation of said control means to close said communication a chosen time interval after movement of said application valve device to application position, means responsive to a change in signal indication adapted to effect movement of said application valve device to lap position, and means controlled by said brake valve device operative to prevent movement of said application valve to application position upon a change in signal indication if said brake valve device is operated to effect a reduction in brake pipe pressure.

24. In a train control equipment, in combination, apparatus set in operation upon a change in signal indication for effecting an automatic train control application of the brakes, means for delaying the operation of the apparatus to effect an application of the brakes for a predetermined period of time after being set in operation, a brake valve device operative to effect an application of the brakes, means operative upon the operation of the brake valve device within said predetermined period of time to a brake applying position for rendering said apparatus ineffective to effect an application of the brakes, and means operative upon the operation of said apparatus to a brake applying position for moving the brake valve device to a position where it is ineffective to influence the train control application of the brakes.

25. In a train control equipment, in combination, apparatus set in operation upon a change in signal indication for effecting an automatic train control application of the brakes, means for delaying the operation of the apparatus to effect an application of the brakes for a predetermined period of time after being set in operation, a brake valve device having a release position, a lap position and an application position and operative manually from release position to service position to effect an application of the brakes, means operative upon the operation of the brake valve device within said predetermined period of time to application position for rendering said apparatus ineffective to effect an application of the brakes, and means operative upon the operation of said apparatus to a brake applying position for moving the brake valve device from release position to lap position to render the brake valve ineffective to in-

fluence the train control application of the brakes.

26. In a train control equipment, in combination, apparatus set in operation upon a change in signal indication for effecting an automatic train control application of the brakes, means for delaying the operation of the apparatus to effect an application of the brakes for a predetermined period of time after being set in operation, a brake valve device operative to effect an application of the brakes, means operative by fluid under pressure supplied by said brake valve device upon the operation of the brake valve device within said predetermined period of time to a brake applying position for rendering said apparatus ineffective to effect an application of the brakes, and means operative upon the operation of said apparatus to a brake applying position for moving the brake valve device to a position where it is ineffective to influence the train control application of the brakes.

27. In a train control equipment, in combination, apparatus set in operation upon a change in signal indication for effecting an automatic train control application of the brakes, means for delaying the operation of the apparatus to effect an application of the brakes for a predetermined period of time after being set in operation, a brake valve device operative to effect an application of the brakes, means operative upon the operation of the brake valve device within said predetermined period of time to a brake applying position for rendering said apparatus ineffective to effect an application of the brakes, and pressure responsive means operative under the control of said apparatus when the apparatus operates to effect an application of the brakes for moving said brake valve device to a position where it will be ineffective to interfere with the train control application of the brakes.

28. In a train control equipment, in combination, apparatus set in operation upon a change in signal indication for effecting an automatic train control application of the brakes, means for delaying the operation of the apparatus to effect an application of the brakes for a predetermined period of time after being set in operation, a brake valve device operative to effect an application of the brakes, means operative upon the operation of the brake valve device within said predetermined period of time to a brake applying position for rendering said apparatus ineffective to effect an application of the brakes, means subject to the opposing pressures of fluid and a spring and operative by said spring upon a reduction in the pressure of fluid acting on said means for moving said brake valve device to a position where it will not interfere with the train control application of the brakes, and means included in said apparatus for reducing the pressure of fluid acting on said means when the apparatus operates to effect a train control application of the brakes.

29. In a train control brake equipment, in combination, a brake pipe normally charged with fluid under pressure, apparatus operative upon a change in signal indication to effect a reduction in brake pipe pressure to apply the brakes, a brake valve device operative manually for controlling the brakes, said brake valve device having a release position in which fluid under pressure is supplied to the brake pipe, a lap position in which the supply of fluid under pressure to the brake pipe is cut off and an application

position in which a reduction in brake pipe pressure is effected to apply the brakes, and means operative upon the operation of said apparatus to effect a reduction in brake pipe pressure to move the brake valve device from said release position to lap position.

30. In a train control brake equipment, in combination, a brake pipe normally charged with fluid under pressure, a valve device movable to 10 a position for effecting a reduction in brake pipe pressure to apply the brakes, a valve operative to effect a second reduction in brake pipe pressure, means operative upon a change in signal 15 indication to effect the operation of said valve device to said position, means controlled by said valve device for actuating said valve to effect said second reduction in brake pipe pressure, means for relaying the operation of the first mentioned means for a predetermined period of 20 time after the initiation of a signal indication, a brake valve device, means operative in a brake applying position of the brake valve device for suppressing the operation of the first mentioned means provided said predetermined period of 25 time has not expired, and means operative after said predetermined period of time has expired for actuating said brake valve device to a position where it is ineffective to control the application 30 of the brakes.

31. In a train control brake equipment, in combination, a brake pipe, a brake valve device having a brake releasing position, a lap position and a brake applying position and being operative 35 manually to said positions to control the brakes, mechanism adapted to be operated upon a change in signal indication to move said brake valve device from said brake releasing position to said lap position and to effect an application of the 40 brakes, means for delaying the operation of said mechanism for a period of time following the change in signal indication, and means controlled by the brake valve device operative to suppress the operation of the mechanism only if the brake 45 valve device is moved to said brake applying position before said period of time has expired.

32. In a train control brake equipment, in combination, a brake pipe, a brake valve device having a brake releasing position, a lap position and a brake applying position and being operative 50 manually to said positions to control the brakes, mechanism adapted to be operated upon a change in signal indication to move said brake valve device from said brake releasing position to said lap position and to effect an application of the 55 brakes, means for delaying the operation of said mechanism for a period of time following the change in signal indication, and means operated by fluid under pressure supplied by the brake valve device when the brake valve device is in 60 said brake applying position for suppressing the operation of the mechanism provided the brake valve device is moved to the brake applying position before said period of time has elapsed.

33. In a train control brake equipment, in combination, a brake pipe normally charged with fluid under pressure, a valve device movable to a position 65 for effecting a reduction in brake pipe pressure to apply the brakes and for establishing a communication through which fluid under pressure is adapted to be supplied to the brake pipe, means normally closing said communication to the brake pipe and operative to permit the flow of fluid through the communication to the brake pipe to compensate for leakage of fluid under 70 pressure from the brake pipe, a valve operative 75

to effect a second reduction in brake pipe pressure, means operative upon a change in signal indication to cause said valve device to move to said position, a valve operative to cut off the supply of fluid under pressure through said communication, and means controlled by said valve device for actuating the first mentioned valve to effect said second reduction in brake pipe pressure and for actuating the second mentioned valve to cut off the supply of fluid under pressure 10 through said communication.

34. In a train control brake equipment, in combination, a brake pipe, a brake valve device having a release position in which fluid under pressure is supplied to the brake pipe, two application 15 positions in each of which fluid under pressure is vented to effect a reduction in brake pipe pressure and a lap position between said application positions in which the supply of fluid under pressure to the brake pipe is cut off, a handle operable manually to selectively move said brake valve device to any one of said positions, and means controlled by traffic conditions to effect the automatic operation of said brake valve device to said lap position.

35. In a train control brake equipment, in combination, a brake pipe, a brake valve device having a release position, an application position, a lap position, and another application position, said positions being arranged in the order in 30 which they are specified, means operable manually for moving the brake valve device selectively to any one of said positions, and means automatically operative upon a change in signal indication for moving the brake valve device from 35 said release position to said lap position.

36. In a train control equipment, in combination, a brake pipe normally charged with fluid under pressure, an equalizing discharge valve mechanism operative to vent fluid under pressure 40 from the brake pipe, a valve device operative upon a change in signal indication to a position to effect the operation of said equalizing discharge valve mechanism to vent fluid under pressure from the brake pipe, a valve operative to 45 effect the operation of the equalizing discharge valve mechanism to vent fluid under pressure from the brake pipe, and means controlled directly by said valve device, with the valve device in said position, to effect the operation of said 50 valve.

37. In a train control equipment, in combination, a brake pipe normally charged with fluid under pressure, an equalizing discharge valve mechanism operative to vent fluid under pressure 55 from the brake pipe, a valve device operative upon a change in signal indication to a position to effect the operation of said equalizing discharge valve mechanism to vent fluid under pressure from the brake pipe, a valve operative to effect 60 the operation of the equalizing discharge valve mechanism to vent fluid under pressure from the brake pipe, and means controlled by said valve device and independently of the pressure of fluid vented from the brake pipe to effect 65 the operation of said valve.

38. In a train control brake equipment, in combination, a brake pipe normally charged with fluid under pressure, a brake valve device operative 70 manually to control the brakes, said brake valve device having a brake releasing position in which fluid under pressure is supplied to the brake pipe and having a lap position in which the supply of fluid under pressure to the brake pipe is cut off, means adapted to be automatical- 75

ly operated to move the brake valve device from said brake releasing position to said lap position, a valve device movable to a position for effecting a reduction in brake pipe pressure and to effect the operation of said means, a valve operative to effect a second reduction in brake pipe pressure, means operative upon a change in signal indica-

tion to effect the operation of said valve device to said position, and means controlled by said valve device, when it is in said position, for effecting the operation of said valve to effect said second reduction in brake pipe pressure.
